UNITED STATES PATENT OFFICE.

WILLIAM B. ALLEN AND HENRY ALLEN, OF PITTSBURG, KANSAS

GRAIN-SCOURER.

SPECIFICATION forming part of Letters Patent No. 759,221, dated May 10, 1904.

Application filed July 27, 1903. Serial No. 167,186. (No model.)

To all whom it may concern:

Be it known that we, WILLIAM B. ALLEN and HENRY ALLEN, citizens of the United States, residing at Pittsburg, in the county of 5 Crawford and State of Kansas, have invented a new and useful Grain-Scourer, of which the following is a specification.

This invention relates to machines for scouring grains of various kinds, such as wheat and 10 corn; and it has for its object to provide a device by means of which the cleaning and scouring may be effected in a perfect, thorough, and rapid manner.

Our invention especially relates to the construction of the scouring-cylinder, which is 15 provided with a plurality of radially-extending screw-threaded teeth whereby the hulls of the grains shall be subjected to a rasping action, which is very effective in causing the said 20 grains to be scoured or their hulls removed, if desired, thus, for instance, converting corn into hominy.

Our invention further consists in certain 25 improvements in the detailed construction and arrangement of parts, which will be hereinafter fully described, and particularly pointed out in the claims.

In the accompanying drawings we have 30 shown a simple and preferred form of our invention; but we desire it to be understood that we do not thereby necessarily restrict ourselves to the precise structural details shown, but reserve the right to all changes and modifications within the scope of our invention 35 which may be resorted to without departing from the spirit or sacrificing the efficiency of the same.

In said drawings, Figure 1 is a front view of a machine constructed in accordance with 40 the principles of our invention, the machine being shown partly in section. Fig. 2 is a transverse sectional view of the scouring-cylinder removed from its casing. Figs. 3 and 45 4 are detail views illustrating modifications in the construction of the scouring-cylinder. Fig. 5 is a detail side view showing another modification of the scouring-cylinder. Fig. 6 is a sectional detail view taken through the

foraminous cylinder and the sleeve adjustable thereon.

Corresponding parts in the several figures are indicated by similar numerals of reference.

The scouring-cylinder, which constitutes the principal part of our invention and which in the drawings has been designated 1, is composed of a cylindrical core 2, a surrounding band 3, which may be of leather, rubber, or any material or composite material suitable for the purpose, and a plurality of radially-extending screws 4, which extend through the 55 flexible band 3, with their heads abutting upon the perimeter of the cylinder and with their points extending outwardly, as shown. The screws employed need not be of any special construction, inasmuch as ordinary wood-screws of proper dimensions may be used with 60 excellent results.

While we have thus far described the scouring-cylinder as consisting simply of the core, the flexible band, and the radiating screws, 70 we have in the preferred form of our invention (illustrated in Figs. 1 and 2) shown two bands of sheet metal—namely, an inner band 5 and an outer band 6. The inner band 5 has been shown as surrounding the wooden 75 cylindrical core 2, the heads of the screws 4 abutting upon the outer surface of said metallic band. The band 6 is disposed exteriorly of the flexible band 3 and is provided with appropriately-disposed perforations, through 80 which the screws 4 are extended. When this construction is employed, it is obvious that the heads of the screws are steadied and supported by contact with the metallic band 5, which will not readily yield to the pressure 85 of the screw-heads, as would a wooden surface. The outer metallic band 6 likewise braces the points of the screws 4 and by so doing prevents injury to the flexible band in which they are mounted.

Many other modifications may be resorted to within the scope of our invention. Thus it is obvious that instead of a metallic-faced cylinder a metallic cylinder may be used. Again, as shown in Fig. 3, the screws 4 may 95 be extended not only through the flexible

band, here designated 3^a, but through the outer and inner metallic bands, here designated 6^a 5^a, as well. Again, as shown in Fig. 4, an inner metallic band, here designated 5^b, 5 may be used in connection with the surrounding flexible band, here designated 3^b, the screws being extended through the latter only to the outer side of said band. Between the 10 rows of screws are secured separate strips 6^c of sheet metal, which by abutting against the projecting portion of the screws will assist in sustaining the latter in position. The strips 6^c may be nailed or otherwise secured to the cylinder. It will be understood from the 15 foregoing description that our scouring-cylinder is composed, essentially, of a cylindrical body having radially-extending teeth, the said teeth being in the shape of screws, the spiral flanges of which practically serve as 20 rasps, which by contacting with the grain serve to effect the scouring or hulling in a very ready, speedy, and satisfactory manner. Incidentally these radially-extending "scouring-screws," as they may be termed, are connected 25 flexibly with the core of the cylinder through the medium of the flexible band in which they are mounted. This feature is of great importance, inasmuch as while a reasonable degree of stiffness should be 30 provided, absolute rigidity of the radially-extending screws is not desirable, and inasmuch as the device if the flexible band alone were used would be liable to rapid wear, whereby the position of the screws might be 35 disturbed, we avail ourselves of the auxiliary metallic bands, which without interfering with the necessary flexibility of the radial screws will brace the latter, cause them to retain their desired position, and also protect 40 the flexible band against rapid wear.

With regard to the disposition of the screws with relation to the cylinder it will be seen by reference to Fig. 4 that said screws are disposed spirally, this being for the purpose 45 of causing the material that is operated upon to be fed during operation from one end of the inclosing casing to the other, or, in other words, from the feed to the discharge end.

In Fig. 1 of the drawings our improved 50 scouring-cylinder has been mounted for operation in a foraminous casing 7, which is suitably mounted within an outer casing 8. A shaft 9, extending through the core of the scouring-cylinder, has bearings 10 in the ends 55 of the outer casing, and said bearings support lubricating-cups 11 of ordinary construction. The foraminous cylinder 7 has closed ends 12 and 13, which, as shown in Fig. 1, may constitute the heads of the outer casing, and one 60 of these heads carries the feed-spout 14, while the other has a discharge-opening 15, capable of being closed by means of suitably-constructed slides 16. The bottom of the outer

casing is also provided with an opening 16 for the escape of the scourings. It is obvious 65 that, according to the different purposes for which the machine is to be utilized, the construction of the casing may be altered and modified to any extent within the scope of our invention; but inasmuch as changes of this 70 character are generally known and well understood it is not deemed necessary further to describe or illustrate them in connection with the present application, with the exception that in Fig. 1 the foraminous cylinder 11 has 75 been shown as provided at opposite ends thereof with perforations 20 and 21, the former of which are much larger than the latter, these being the ones which are exposed and in active use when corn is being operated upon. The 80 foraminous cylinder is also shown as being partly inclosed for about one-half its length by a movable sleeve 22, which has openings of a size corresponding with the size of the small openings 21. When corn is being operated upon, only one-half of the cylinder—namely, that having the large openings 20—will be exposed for active use, while when grain, such as wheat, is being operated upon the sleeve 22 will be shifted over the portion 90 of the cylinder having the large openings 20, which latter readily admit of the passage of the wheat-scourings to and through the openings in said sleeve portion 22. It may be stated also that in many cases a fan and suitable connections will be used for the purpose of removing the waste matter and thoroughly cleansing the output; but such fan and connecting-ducts being very well known in the 95 art they have not been shown.

From the foregoing description, taken in connection with the drawings hereto annexed, the operation and advantages of our invention will be readily understood by those skilled in the art to which it appertains. It combines 100 simplicity and ease of operation with efficiency and general utility. It may be constructed at a moderate expense, and an important feature which should not be lost sight of is this, that our improved machine, while applicable 105 to a variety of uses, occupies very little space and is therefore in all respects economical and useful.

Having thus described our invention, we 110 claim—

1. In a device of the class described, a scouring-cylinder comprising a core, a metal facing, a flexible band surrounding said facing, a metallic band surrounding said flexible band, and a plurality of screws extending radially 115 through the flexible band and the exterior metallic band, the heads of said screws being supported against the exterior surface of the metallic facing.

2. In a device of the class described, a foraminous cylindrical casing having large 120

openings at one end and small openings at the other end thereof, in combination with a sleeve slidable on said cylinder and having small openings corresponding in size with the 5 small openings in said cylinder, an exterior casing and an interiorly-disposed scouring-cylinder having radially-extending screw-threaded teeth.

In testimony that we claim the foregoing as our own we have hereto affixed our signatures in the presence of two witnesses.
